ATTORNEY

UNITED STATES PATENT OFFICE

SAMUEL M. LERNER, OF LOS ANGELES, CALIFORNIA

SASH HOLDER

Application filed February 23, 1927. Serial No. 170,119.

As may be inferred from the above title, this invention relates to means for holding window sashes; and it is an object of this invention to provide reliable resilient means for yieldably holding window sashes at desired levels, as the same may be opened for ventilation or other purposes, without the use of counterweights, or the like.

It is an object of this invention to provide, at the edges of window stiles, and in engagement with those oppositely disposed vertical surfaces thereof which extend parallel with jambs, resiliently pressed frictional means for yieldably holding sashes at any desired level; and preferred embodiments of my invention, including vertical strips interposed between window stiles and window jambs, may utilize suitably spaced coil springs, extending wholly or partially through said jambs,—yieldably forcing the mentioned vertical strips, from opposite sides, toward the mentioned faces of window stiles.

It is a further object, employing window sashes of slightly reduced outside diameter, or employing window frames that include jambs which are spaced apart by a slightly greater distance, (in proportion to the diameter of sashes) than has heretofore been common, to provide simple and easily insertible concealed means serving not only to hold said window sashes in elevated positions, to which they may be manually or otherwise lifted, but also to take up any lateral play in said window sashes,—substantially excluding inclement weather and preventing the rattling of windows during wind storms.

Other objects of my invention, essential parts of which (excepting the mentioned vertical strips) are concealed in use, may be best appreciated from the following description of an illustrative embodiment thereof (and from an alternative embodiment, in which I provide means for adjustment) taken in connection with the appended claims and accompanying drawings, in which

Fig. 1 is a partial elevational view of a two-sash window in which my invention is employed, parts being broken away.

Fig. 2 is a horizontal sectional view, taken

substantially as indicated by the line 2—2 of Fig. 1.

Fig. 3 is a diagrammatic view, corresponding to a portion of Fig. 1, but illustrating an alternative form.

Referring to details of that specific embodiment of my invention chosen for purposes of illustration, 11 being a window frame which comprises vertical jamb elements 12, I show an upper sash 13 as comprising stiles 14; and I show a lower sash 15 as comprising stiles 16.

Each stile 14 being provided with a usual vertical surface 17, and each stile 16 being provided with a vertical surface 18, and the said vertical surfaces being disposed at the same horizontal distance from vertical surfaces 19, provided by jamb members 14, I interpose between the mentioned vertical surfaces, in the case of a two-sash window, two wooden or other strips 20, 20',—each preferably corresponding in length to the total height of a window opening and corresponding in breadth to the front-to-back thickness of the respective window stiles.

A central guide strip 21 and additional 75 guide strips 22 and 23 being so spaced apart, as by suitably securing the same to jambs 12 and to strips 24, (to which latter an outside trim or facing element 25 is shown as secured) as to permit a reasonable play of the strips 80 20 therebetween, I show the latter as constantly pressed into engagement with the stiles 20, 20' by spiral springs 26,—the latter being preferably retained, in openings 27, such as may be cut in the jamb elements 12, 85 in case said openings are cut entirely through said jambs, by means such as sheet metal elements 28, shown as secured by screws 29.

In the alternative embodiment of my invention illustrated in Fig. 3, the holes or 90 openings 27^a are shown as cut only part way through a jamb element 12^a; an optional sheet metal element 28^a is shown as having the form of a thimble comprising an inner flange 29^a; and, in order to provide for convenient adjustment of springs such as are shown at 26^a, interiorly threading a tubular element 30^a (shown as secured by screws 31^a extending through ears 32^a) I provide an externally threaded stop 33^a with a nick 34^a, 100

accessible through an opening 35^a, in which the tubular element 30^a may be secured.

Essential features of my inventions being illustrated in Figs. 1 and 2, it will be appreciated that the power of the springs 26^a is intended to be so proportioned relatively to the weight of the sashes 13 and 15 that, although said sashes may be manually movable without difficulty, the said sashes shall always remain in any position to which they may be adjusted; and the modification illustrated in Fig. 3 should accordingly be understood merely to disclose features, not ordinarily necessary, which may be employed in superior buildings or in regions where climatic changes render adjustability important.

Although I have herein described a single typical embodiment of my invention, suggesting one alternative embodiment thereof, it should be understood not only that various features thereof might be independently employed but also that all embodiments thereof are intended effectively to hold window sashes in any positions to which they may be adjusted, and to prevent entrance of rain or wind, and largely or completely to obviate rattling of window sashes; and also that numerous modifications of my invention, additional to those mentioned above, might easily be devised, by workers skilled in the arts to which this case relates, without involving the slightest departure from the spirit and scope of my invention, as the same is indicated above and in the following claims.

I claim as my invention:

1. In means for yieldably supporting a sash in a window opening at any level to which it may be adjusted relatively to a fixed jamb member; a substantially flat vertical strip interposed between a sash member and said jamb member; and means resiliently pressing said strip toward one of said members,—said resilient means being proportioned in strength to the pressure required to hold said window and provided with adjusting means accessible through openings in said strips; said adjusting means comprising an internally threaded member mounted in said strip, and an externally threaded cap movable in said member.

2. For use in combination with a window sash and a window frame having jambs in the sides thereof; a sash holder embodying a substantially flat vertical strip interposed between said sash and a jamb in said frame, said strip being provided with a plurality of apertures; internally threaded tubular members mounted in said apertures; coil springs engaging the side of said jamb and extending into said tubular members; and externally threaded adjustable caps mounted in said tubular members engaging the outer ends of said coil springs.

3. For use in combination with a window

sash and a window frame having jambs in the sides thereof; a sash holder embodying a substantially flat vertical strip interposed between said sash and a jamb in said frame, said strip being provided with a plurality of apertures; internally threaded tubular members mounted in said apertures; coil springs engaging the side of said jamb and extending into said tubular members; and externally threaded adjustable caps mounted in said tubular members engaging the outer ends of said coil springs, said jamb members being provided with openings coaxial with the openings in said strip and adapted to receive one end of said springs.

4. In means for yieldably supporting a sash in a window opening at any level to which it may be adjusted relatively to a fixed jamb member provided with a plurality of transverse apertures; a substantially flat vertical strip interposed between a sash member and said jamb member; and means resiliently pressing said strip toward one of said members,—said resilient means comprising separate springs mounted in said transverse apertures which are restrained against outward movement by sheet metal plates mounted on said jamb over the outer ends of said transverse openings and are restrained against inward movement by adjustable cap means mounted in said transverse apertures.

In testimony whereof, I have hereunto set my hand at Los Angeles, California, this 17th day of February, 1927.

SAMUEL M. LERNER.
